UNITED STATES PATENT OFFICE

2,268,435

SHOE AND FOOT SAVER

Victor Zucker, Omaha, Nebr.

Application June 30, 1941, Serial No. 400,379

2 Claims. (Cl. 36—72)

The present invention relates to workmen's shoes and has for an object to provide means for protecting said shoes and the forward portions of workmen's feet for not only preventing undue wear on said shoes but also to protect the insteps and toes of workmen at times when, resultant from accident, a comparatively heavy object is dropped toward the instep or toe of a shoe.

Another object of the invention is to provide a device for the above stated purposes which is so constructed that an entrance of debris, sand and the like is prevented at times when the protective device is in use upon a workman's shoe and foot.

A further object of the invention is to provide a device so constructed that the instep, toe and sides of a workman's shoe is prevented from contact with said device during use whereby a shoe of ornate appearance may be worn during working hours without the necessity, as heretofore, of a workman changing his shoes upon arrival at work.

A still further object of the invention is to provide a device for use with shoes equipped with rubber heels and having a rubber outsole whereby the new device may be worn advantageously during work in munition factories and noiselessly.

Other and further objects and advantages of the invention will be understood from the following detailed description thereof, reference being had to the accompanying drawing in which:

Figure 1 is a side elevation of the new device applied to a shoe in a position of use.

Figure 2 is a longitudinal vertical section of the new device, said shoe being omitted.

Figure 3 is a top plan view thereof, a certain strap and buckle preferably employed not being shown.

Figure 4 is a transverse vertical section, the view being taken substantially on line 4—4 of Figure 2.

Referring now to the drawing for a more particular description, 10 indicates generally a workman's shoe of semi-ornate appearance having a sole 12, heel 14, rubber heel cap 15, instep 16 and toe 18.

The new device includes a housing made primarily and preferably of steel shaped complementary to and for receiving therein the forward portion of the shoe 10. The housing includes a sole portion 20, a toe portion 22, an instep portion 24 and an extended portion 25 of said sole portion, said extension projecting further rearwardly and towards the heel 14 of the shoe 10,

in use, than said instep portion 24, as best shown in Figure 2.

The housing may be formed integral of pressed steel or said housing may be spun in approximately the form of a frustrated cone and later crushed to said complementary shape by means of die press operations.

The new device further includes a rubber outsole 26 secured by any suitable means such as cement or the like to the bottom of the sole portion 20 of the housing.

Also said sole portion 20 may be made separate from the other portions of the device and attached to said other portions by any suitable means.

A rubber shim or strip 28, preferably formed of sponge rubber, is vertically disposed against the inner sides of the side walls 27 of the new device adjacent the sole 20 thereof, said shim or strip 28 having a portion 29 which is arcuate in plan disposed around and within the toe portion of the housing, as best shown in Figure 2, for purposes later described. The strip 28 together with a later mentioned strip and portions of said strips are secured to the housing preferably by means of a suitable cement.

The new device further includes a second rubber strip 30 disposed, as best shown in Figure 4, within and against each side wall of the housing adjacent the mouth 34 of the latter, said strip 30 having a portion 32 disposed against and across the inner surface of the instep portion 24 of the housing for purposes later described.

The strip 30 may be formed integral, if desired, with the shim or strip 28, said strip 30 being preferably thicker than the shim or strip 28.

Either one or both of said strips may be formed integral with a third rubber strip 46 which, as best shown in Figure 3, is substantially arcuate in plan, having ends 47 extending from the members 30 and 28 across the extended portion 25 of the sole 20 of the new device as best shown in Figure 2.

The instep portion 24 of the housing is upwardly turned as at 36 whereby free bending movements of the forward portion of the shoe 10 are permitted during walking movements and at times when the said shoe and new device are upon a workman's foot in use.

Means are provided for removably attaching the new device in a position of use upon the shoe, said means preferably including a pair of oppositely disposed ears 38, which preferably are made of metal and spot welded to the side walls 27 of the new device adjacent the instep portion

thereof and in instances where said ears are formed of flexible material, said ears are secured by means of rivets, not shown, in the said position as shown in Figure 3.

Each ear includes an apertured portion 48 for receiving through said apertures the looped ends 41 of oppositely disposed straps 42. The free end of one of said straps is provided with a buckle 43 and the other said strap is provided with spaced apart apertures 44 whereby the new device may be secured, as shown in Figure 1, to the shoe 10.

Referring to Figure 1 it will be understood that, as indicated by the dotted lines, there is an appreciable distance between the inner surface of the new device and the toe 18 of the shoe 10.

As thus described it will be understood that at times when the new device is in a position of use the bottom of the sole of the shoe 10 is snugly abutted against the rubber member 46 and the sides of said sole are abutted against the rubber member 28 and that the rubber member 30 together with the portion 32 of the latter are snugly abutted against and across the instep and sides of the shoe whereby debris is prevented from entering the interior of the housing during use and the edges of the sole of the shoe are prevented from contact with said housing and, therefore, prevented from becoming scuffed and roughened during use.

In operation bending movements of the shoe 10 adjacent the ball of a user's foot are permitted, said sponge rubber facilitating the same while at the same time the forward portion of the shoe is enclosed within the housing of the new device during said bending.

From the foregoing description it is thought to be obvious that a shoe and foot saver constructed in accordance with my invention is particularly well adapted for use by reason of the convenience and facility with which it may be assembled and operated, and it will be obvious that my invention is susceptible of some change and modification without departing from the principles and spirit thereof and for this reason I do not wish it to be understood as limiting myself to the precise arrangement and formation of the several parts herein shown in carrying out my invention in practice except as claimed.

I claim:

1. A shoe and foot saver comprising a metallic housing having an instep-toe portion and a sole portion, means for securing said housing about the forward portion and over the instep and toe of said shoe, said sole portion having an extension disposed further toward the heel of said shoe than said instep portion, a rubber strip disposed across said instep portion and extending to said sole portion at each side of and within said housing, said strip having a portion disposed across said extension of said sole portion for preventing debris from entering said housing during use, and a second rubber strip disposed around the toe portion and at each side of and within said housing adjacent said sole portion for preventing contact of the edges of the sole of said shoe with said housing.

2. A shoe and foot saver as described in claim 1 which further includes a rubber outsole secured to the outer side of the sole portion thereof.

VICTOR ZUCKER.
